JAMES S. CROSSLEY, OF SOLVAY, NEW YORK, ASSIGNOR TO PASS & SEYMOUR, INC., OF SOLVAY, NEW YORK, A CORPORATION.

RECEPTACLE FOR INCANDESCENT ELECTRIC LAMPS.

1,081,581.

Specification of Letters Patent.

Patented Dec. 16, 1913.

Application filed December 31, 1910. Serial No. 600,304.

To all whom it may concern:

Be it known that I, JAMES S. CROSSLEY, a citizen of the United States, residing at Solvay, in the county of Onondaga and 5 State of New York, have invented new and useful Improvements in Receptacles for Incandescent Electric Lamps, of which the following is a specification.

My invention relates to water-proof receptacles for incandescent electric lamps and consists in certain improvements in the formation of the porcelain body whereby the lamp terminals are better insulated and more correctly maintained in position and 15 the manufacture of the device is simplified.

The essential feature of my improvement is a plurality of integral ribs in the interior of the porcelain body or cup preferably formed as shown.

20 My invention is illustrated in the drawing herewith in which the reference numerals of this description are used to indicate the same parts in all the figures.

Figure 1 is a vertical longitudinal section 25 of the complete receptacle, taken on line *a—a* of Fig. 4. Fig. 2 is a similar vertical section taken on line *b—b* of Fig. 4. Figs. 3 and 4 are respectively top and bottom plan views of the porcelain body of the receptacle. Fig. 5 is a vertical sectional view of 30 the porcelain body.

In the figures 1 indicates the body, or cup, made of porcelain, or of other suitable insulating material, having the usual external 35 form. It is provided with the holes 2 2 for the conductors 3 3 and with the intermediate hole 4 for the running in of the insulating cement. On the interior of the cup are molded the longitudinal ribs 5 5 preferably terminating in the beveled ends 6 a short distance from the margin of the cup and preferably extending up to the base for convenience in molding. There should 40 be at least three or four of these ribs for 45 two would accomplish only in an imperfect degree the result of centering the terminals and maintaining them true.

In the process of manufacture, the outer screw-threaded lamp terminal 7 and the 50 inner terminal 8 are usually provided each with a short length of conductor cord before being arranged and secured in the porcelain body. They may desirably be initially assembled as here indicated in connection with a porcelain button 10 fitted to

a groove 9 in the threaded shell, and having a recess 11 in its upper surface to permit the soldering of one conductor to the inner, or central, terminal 8. Said terminal has a bushing fitting a central hole in the 56 button in which the conductor wire may be inserted giving a good contact and a strong connection. The other conductor may be soldered to the exterior of the shell at any suitable point. 65

When the terminals have been assembled and the conductors soldered thereto, the parts are set in the cup from the mouth end with the conductors extending through the respective holes, and are then pressed, or 70 pulled, home, with the flaring end 14 of the shell fitting the beveled ends 6 of the ribs. These ribs thus insure the parts assuming the correct position in the cup as shown in Fig. 1 with the flaring end of the 75 outer terminal pressed against the beveled ends of the ribs and the margin of said end fitting close to the porcelain at all points. Considerable and sufficient space is left 80 around and above the terminals, which may be filled with an insulating cement securing the parts firmly in place.

Having described my invention, I claim,

1. In a water proof receptacle for incandescent electric lamps, a cup-shaped body 85 of insulating material having a plurality of ribs on its inner surface extending from about the base nearly, but not quite, to the margin of the cup, said ribs having their marginal ends beveled, a substantially tubular outer lamp terminal, having a flaring outer end, said terminal being set in the body substantially in contact with the ribs and having said flaring end arranged in engagement with the beveled ends of the 90 ribs and the margin of said end fitting snugly the inner wall of the cup, a central lamp terminal suitably secured in the base 95 of the cup, and insulating cement filling the space within the cup around the outer terminal and between the ribs. 100

2. In a water-proof receptacle for incandescent electric lamps, a cup-shaped porcelain body provided with a recess for the lamp terminals, the wall of said recess being provided with a series of ribs for engaging with and maintaining in correct position the outer lamp terminal, said ribs being continuous and of equal length and extending from the upper, closed end of the 110

recess down nearly to the mouth of the recess and terminating a short distance within said mouth in beveled ends.

3. A water-proof receptacle for incandescent electric lamps comprising a porcelain cup having an open mouth at its lower end and three holes through the wall which closes its upper end, a series of integral ribs on the inner surface of the cup terminating a short distance within the mouth of the cup in beveled ends, a threaded, tubular, lamp terminal set in the cup and having a flaring end engaging with said ends, a small center terminal suitably insulated and ar-

ranged at the upper end of the tubular terminal, conductors extending in through two of said holes and connected to the respective terminals and insulating cement filling the spaces between the terminals and the wall of the cup, substantially as described and shown. 15

In testimony whereof I have signed my name to this specification in the presence of two subscribing witnesses.

JAMES S. CROSSLEY.
